UNITED STATES PATENT OFFICE.

CLINTON A. TOWER, OF CLEVELAND, OHIO, ASSIGNOR TO THE EMPIRE CAR COUPLER COMPANY, OF WEEHAWKEN, NEW JERSEY.

CAR-COUPLING.

SPECIFICATION forming part of Letters Patent No. 484,125, dated October 11, 1892.

Application filed March 14, 1892. Serial No. 424,757. (No model.)

To all whom it may concern:

Be it known that I, CLINTON A. TOWER, of Cleveland, in the county of Cuyahoga and State of Ohio, have invented a certain new and useful Improvement in Car-Couplers, of which the following is a specification.

I will describe a car-coupler embodying my improvement, and then point out the novel features in a claim.

10 In the accompanying drawings, Figure 1 is a top view of a draw-head embodying my improvement. Fig. 2 is a horizontal section of the same. Fig. 3 is a central longitudinal section. Fig. 4 is a transverse section taken 15 at the plane of the dotted line xx , Fig. 1. Fig. 5 is a perspective view of a dog or block and appurtenances.

Similar letters of reference designate corresponding parts in all the figures.

20 A designates a draw-head. As shown, it is pivoted at its forward extremity. It has a shank or bar a, which may be fastened to a car in the ordinary manner.

B designates a knuckle of the draw-head. 25 It consists of an elbow-lever fulcrumed between its ends by a pin C to one of the bifurcate extremities of the draw-head. The outer portion of the knuckle B is forked, so that an ordinary coupling-link may be inserted within it, and is provided with holes for the reception of an ordinary coupling-pin. The inner part of the knuckle is shown as tapering toward its extremity and at the extremity is rounded on its under side, and also on that 35 side which is foremost when this end of the coupler swings into the draw-head, the object of thus rounding the extremity being to enable it to automatically force back a dog or block D, by which it is to be retained when in 40 use. The dog or block D extends upwardly from a rock-shaft D'. This rock-shaft D' has a bearing at one end in a projection a', formed in the draw-head, and is supported at the other end by passing through and fitting a hole in 45 the side of the draw-head. Its outer end is provided with an arm d, whereby it may be rocked. The upper end of the dog or block when in an operative position fits between two projections a² a³, whereby it is sustained

against lateral strain. A bridge a⁴ may extend between the projection a' and the projection a³ to aid in sustaining the dog or block laterally. It will be seen that the forward corner of the dog or block is rounded, so that when the inner end of the knuckle contacts 50 with it the dog or block will be forced rearwardly to allow the passage of the knuckle beyond it. The arm d forms a counter-weight which will always bring the dog or block to its operative position when permitted to do 55 so. A pin a⁵ on the exterior of the draw-head prevents the arm d from dropping too far down.

If the opening in the side of the draw-head through which the rock-shaft D' passes be 60 suitably shaped and the rock-shaft and its appurtenances are made of malleable metal, the latter may be introduced into place, and afterward the arm d may be bent into the position in which it is illustrated in the drawings 65 to prevent it from assuming a position which will permit of the removal of the rock-shaft with the dog or block.

It will be seen that an essential feature of my present improvement is a dog or block 70 which is carried by and moved with a rock-shaft.

By my improvement I produce a very simple and efficient means for coupling cars and one which will not be liable to get out of order. The forward end of the arm d may have connected to it a chain or analogous contrivance for enabling the attendant of a car to release the coupling. A chain may also be connected between this arm or another arm 80 and a portion of the car, so that in the event of the detachment of the draw-bar through any accident its first forward movement will cause the dog or block to be rocked backward far enough to release the knuckle and disengage the draw-head from the one belonging to the next forward car. This will obviate accidents liable to occur from the falling of a draw-head down upon the road-bed.

What I claim as my invention, and desire 90 to secure by Letters Patent, is—

The combination, with a draw-head and a knuckle consisting of a bell-crank lever ful-

crummed thereto, of a dog or block for directly
engaging with the knuckle, a rock-shaft from
which said dog or block extends, and an arm
connected with the rock-shaft outside the
5 draw-head, constituting a counter-balance for
returning the dog or block to its normal po-
sition, substantially as specified.

In testimony whereof I have signed my
name to this specification in the presence of
two subscribing witnesses.

CLINTON A. TOWER.
